METHOD OF PRODUCING TERMINALS

Norman W. Cummins, Louisville, Ky.

Application July 14, 1932, Serial No. 622,375

10 Claims. (Cl. 29—155.55)

This invention relates to a method for forming "terminals" or "lugs" and the like, such as are attached to the ends of electric cables or wires to expedite and insure good electrical contacts. 5 These terminals are of unitary structure, having a wire receiving end designated as the shank and a flattened end referred to as the tang. The principal object is the production of these widely used articles from the minimum amount 10 of the highest grade material by a reduction in the number of mechanical operations together with definite improvement of the product and a reduction in the cost of production, and at the same time improving the appearance and utility 15 of the product.

To accomplish these ends by the preferred method, it is necessary to employ a part of the process for producing cold upset blanks as disclosed in applicant's co-pending application 20 Serial Number 583,421, filed Dec. 28th, 1931, viz. the sizing of low priced hot rolled unsized or crude copper wire and then severing an exact volume (exact diameter and length) of metal required for the finished product, concurrently with 25 other operations being performed by the same cold upsetting or forming machine.

To assist in an understanding of this invention, reference is had to the accompanying drawings which are incorporated herewith.

30 Figures 1 to 3B inclusive represent preparation of the blank, Figs. 1A, 2A and 3A are end views of their associated figures. Figs. 4 to 8 inclusive represent the blanks after certain forming operations, explained hereinafter, all on substantially a full size scale. Fig. 9 is the side elevation of the forming tools or instrumentalities while Fig. 10 is a top view of a portion of Fig. 9, also shown on a full size scale.

Numeral 10 indicates a section taken from an 40 indeterminate length of hot rolled unsized stock referred to hereinafter as crude stock which is to be forced through a sizing die by a specially constructed heavy duty feed mechanism substituted for the standard relatively light feed equipment, prior to the regular severing operation and thereby make possible the production of uniform socketed terminals, directly from crude stock in place of relatively expensive sized stock and incidently effect a pronounced saving in money as 50 well as enabling the producer to entirely omit the usual individually performed conversion step and at the same time retain the function and result of that step, which is accomplished by the special feed mechanism, operating in 55 connection with an extruding or drawing die,

lodged in the same upsetting machine which forms the terminals.

Numeral 11 indicates the sized stock, while 12 is to indicate the tapering annular section effected by the die while the crude stock is in the 5 process of being converted into sized stock.

The sized stock is severed along the line 2—2 as mentioned supra and is carried over to another die in the same machine for upsetting as indicated in cross sectional view Fig. 2. A second similar operation produces the blank shown in cross section by Fig. 3. Fig. 3B is a cross section of a shorter blank being put through the same steps.

To produce these blanks uniformly without excessively damaging the tools, it is necessary to have the exact quantity of material. In developing this process applicant's first efforts to produce these terminals from hot wire were not successful, owing to the very short life of the tools, especially in producing the blank shown in 3B as well as pronounced intolerable irregularities in length of the socket, all due to the variable volume of metal encountered in the use of raw stock. Further, uniformity of product is desirable if not 25 necessary to procure trade acceptance. However, certain forms of terminals can be produced directly from crude stock.

A supply of blanks as shown in Figs. 3, 3A or 3B, are disposed in a conventional hopper and are automatically picked up by a feed mechanism, a member of which telescopes with socket 14 which is passed to the forming dies shown in Figs. 9 and 10 where it is vertically lodged in the receiving clamp 15, shown by the dotted circle, 35 which is established by semi-circles 15a—16 when the ram or hammer 17 is approaching the closed position as shown in Figs. 9 and 10 and is proceeding for the forming operation which is completed when the face 18 of ram 17 is positioned substantially as shown with reference to face 19 of stationary die 20, which is equipped with a slide 21, also shown in the position it is forced to occupy at the closed position, however, as ram 17 withdraws, slide 21 which is responsive to spring 22, tends to hold it in normal open position indicated by dotted lines 23—24.

It will be perceived that as ram 17 makes its closing stroke with a blank yieldingly supported in clamp 15, that the body portion 14a, Fig. 3 or 50 3B, will be swaged into the form 25 shown in Figs. 9 and 10 partially in full line and partially in dotted lines which constitute the tang of the terminal.

At the beginning of this swaging process, as 55

soon as the blank is caught between the faces of clamp 15 the carrier arm of the feed mechanism, not shown, is withdrawn. As the swaging operation progresses the shank portion 14B which is slidably supported between faces of 15, due to displacement of metal and guiding tapered surface 26 of the die, the shank is affected and moves up and beyond the top surface of said clamp, as shown in Fig. 9, the blank having been originally placed in the clamp with the top surface 14c of shank substantially even with top surface 17a of ram 17.

Upon completion of the swaging, and as the ram is withdrawn, slide 21 under the influence of its spring 22 expels the formed terminal 25. Prior to this expulsion, punch 27 which is slidably mounted in die 20, as indicated in Fig. 9, is driven by cooperating mechanism in the direction of the arrow into die 28 mounted in ram 17 and with which it registers and thereby removes a slug which forms the eye-hole E. The slug falls over into cavity 29 and gravitates through hole 30. Rod 17e is operated by a cam or crank of the upsetting machine to prevent stock from flowing into die 28 during swaging. It is withdrawn to permit function of the eye-holding mechanism.

To eliminate a separate operation the forming face of die 20 is concave along the dotted line 20a, while the forming face of insert 17b of ram 17 is convexed along the dotted line 17f. This is also formed with opening 28 to provide the die for co-operating with punch 27. Forming faces of ram 17 in die 20 can be made flat in which case the terminal could be formed accordingly and as shown in Figs. 4 and 5. The cross sectional view of the terminal as shown in Fig. 6 is taken along the line 6—6 of Fig. 4 which has been formed with concavo-convex surfaces. Fig. 5 is a linear cross sectional view of Fig. 4 when formed with the flat ram or die while Fig. 4a is an end elevation of Fig. 4.

A similar constructed set of instrumentalities as shown in Figs. 9 and 10 with flat forming faces are employed to swage the blanks shown in 3b into a terminal shown in Figs. 7 and 8, the latter being a side elevation of the former.

Attention is directed to the fact that blank shown in Fig. 3, used for forming the terminal illustrated in Figs. 4—4a and 5, is employed where an abnormally large contact surface is desirable such as a "ground" or "mass" connection for conveying high amperage current incident to starting motor equipment as employed on present day internal combustion engines. Blank 3b is formed with a deep socket resembling a cartridge shell in order that there will be a much less quantity of stock to be swaged, which will result in the terminals shown in Figs. 7 and 8 and which are used for installation where they engage metal of relatively high current carrying capacity as contrasted with the ground terminal which is usually installed in contact with ferrous metals.

From these operations the quantity of predetermined metal in blanks 3 and 3b result in terminals with tangs substantially as shown in their companion figures without trimming which contributes to accomplishing the objects of this invention. Although it is preferred to permit the cylindrical stock constituting the tang to develop a normal configuration from the swaging operation for the finished product, it is obvious that trimming or subsequent shaping can be utilized to fashion the tang to many practical forms, one of which is indicated by the dotted line superim-

posed on Fig. 4 and then forming the tang into a cylindrical hollow or arched form as indicated by an end elevational view in Fig. 4B. Cylindrical hollow or concave forms are particularly useful for effecting secure connections, as upon riveting or bolting these tangs to a companion member, closer and more enduring contacts are procured than if they had been left flat. Tangs made with the latter form, even under expert installation, are frequently found to have reversely "curled" or separated at the remote edges, which result in troublesome contacts.

Modifications, extensions, eliminations and combinations can be indulged without departing from the spirit of this invention, therefore I wish to be limited only by the accompanying claims.

I claim:

1. A method for producing an integral terminal from a predetermined volume of cylindrical solid cold copper stock which consists of extruding a portion of a blank so as to have a socket in one end of said stock, slidably supporting said stock by one end of said blank in suitable instrumentalities, while swaging the closed end of said blank by said instrumentalities into a tang. 25

2. A method of producing an integral terminal from a length of solid cold copper stock which consists of upsetting and piercing said stock to form a blank extruding said blank to form a socket in one end of said blank, while maintaining said diameter throughout the length of the socketed portion of said blank then swaging the closed end of said blank into a tang. 30

3. A method of producing an integral terminal from a length of cylindrical solid cold copper stock of substantially uniform diameter which consists of extruding said length of cylindrical stock to form a socket in one end of said stock, by exerting pressure longitudinally thereon while maintaining the first established inside diameter unchanged and maintaining said diameter throughout the length of the socketed portion of said stock then swaging the closed end of said stock into a tang. 35

4. A method for producing an integral terminal from a predetermined volume of cylindrical solid cold copper stock of substantially uniform diameter which consists of lengthwise flowing and thereby forming a socket without changing the inside diameter in one end, by exerting pressure longitudinally thereon, of said stock while maintaining said outside diameter throughout its length then swaging the closed end of said stock into a tang. 50

5. A method of procuring an integral terminal from a length of cylindrical solid cold copper stock of substantially uniform diameter which consists of upsetting and piercing said stock to form a blank extruding said blank to form a socket, having a depth in excess of twice its diameter, in one end of said blank, while maintaining said outside diameter throughout the length of the socketed portion of said blank then swaging the closed end of said blank into a tang. 55

6. A method of producing an integral terminal from a section of cylindrical solid cold copper stock of a given diameter to form a blank, which consists of extruding said blank so as to form a socket at one end of said stock without changing the diameter of said stock, then slidably supporting said blank thus formed while swaging the closed end of said blank into a tang and subsequently piercing an eye in said tang while still being slidably supported. 70

7. The method of producing an integral terminal from a length of solid unheated copper stock comprising the following steps: Severing a length from a supply rod to form a blank, simultaneously piercing one end and upsetting said blank throughout the length of same to a given uniform diameter to form a pierced cylindrical blank, then extruding said blank without materially changing said diameter to produce a socket in said end, 5 said socket having a depth in excess of twice its diameter, swaging the closed end of said blank and a portion of the socket to form a tang.
8. The method of making copper terminals which comprises the following steps: Extruding 10 metal into the form of a solid cold copper rod, cutting a section from said rod to form a blank, and subsequently causing a portion of the unheated metal of the blank to flow longitudinally 15 of the axis of the blank to form a socket at one end without changing the diameter of said blank 20

by exerting pressure longitudinally thereon, then swaging the closed end of said blank into a tang.

9. A method of producing an integral terminal from a length of cylindrical solid cold copper stock of substantially uniform diameter which consists of extruding said length of cylindrical stock to form a socket in one end of said stock, while maintaining said diameter throughout its length, by exerting pressure longitudinally thereon, then swaging the closed end of said stock into a tang. 5

10. A method for producing an integral terminal from a predetermined volume of cylindrical solid cold copper stock of substantially uniform diameter which consists of lengthwise flowing and thereby forming a socket in one end of said stock 15 while maintaining said diameter throughout its length, by exerting pressure longitudinally thereon, then swaging the closed end of said stock into a tang. 10
